UNITED STATES PATENT OFFICE.

KNUT E. WAHLGREN, OF VALLEY STREAM, AND REINHART W. PITTMAN, OF NEW YORK, N. Y.; SAID PITTMAN ASSIGNOR TO SAID WAHLGREN.

CORE-MAKING MACHINE.

Application filed July 24, 1924. Serial No. 727,881.

To all whom it may concern:

Be it known that we, KNUT E. WAHLGREN, a citizen of the United States, and a resident of Valley Stream, county of Nassau, and State of New York, and REINHART W. PITTMAN, a citizen of the United States, and a resident of New York city, county and State of New York, have invented certain new and useful Improvements in Core-Making Machines, of which the following is a specification.

This invention embodies an apparatus, and a method of producing cores for foundry work, especially the class of cores where duplicate work is required in large numbers, such as castings for plumbers' fittings, valves, engine cylinders, and the like. An apparatus made in accordance with the present invention includes means for handling the core boxes in which the cores are molded, that is to say, open the molds, close them, and swing them into the various positions required in one cycle of operation, during which time in the cycle of completing a fully formed core, certain other operations are performed by the operator of the machine, such as placing the sand in the two part mold, the introduction of a wire into one such mold part, the forming of a vent groove in the other, the application of a paste to the surface of the partly formed cores, the joining of the two partly formed cores, the removal of one mold member to leave the fully formed cores in the other mold member, transferring means for engaging the fully formed cores, which means also engages the mold member in which the cores are last stationed, and turning completely over with the mold member, at which time the fully formed cores are on the top of the transferring member. The latter mold member is now returned to its normal position. The transferring member may now be removed from the mold member and together with the fully formed cores therein, put into the drying oven.

An apparatus made in accordance with the present invention includes driving mechanism controlled by a cam disc, said cam disc being turned step by step by the operator of the machine, as the manual labor proceeds in the cycle of operations in the making of a complete core or plurality of cores, the cam disc operates shifter arms that co-act with clutch pulleys. Four such

pulleys are provided, two of which are connected to a carrier frame for controlling the movements of one mold member, and the other two for the carrier frame of the other mold member, one of each set of said clutch pulleys runs reversely to the other, thereby controlling the movements of the mold members to and away from each other as the case may be.

The pulleys are preferably driven by an electric motor, and means such as contact maker and breaker on the cam disc may start and stop the motor in any part of the cycle of operation, the moving of the cam disc controlling all operations.

One object of the invention is to provide an apparatus in connection with the method of producing cores that is simple and reliable in its action and capable of turning out a high class product and an increase in production. A further object is the handling of the mold members mechanically, since the turning of them by hand as is usually done, is laborious work, by our improved means female help and unskilled labor may produce high class core work.

In the drawing showing embodiments of our invention,

Figure 1 is a front elevation of the machine showing the mold members in the closed position.

Fig. 2 is a side elevation showing the upper part of the machine.

Fig. 3 is a plan view of the same.

Fig. 4 shows the two molds in open position to receive the sand in the mold cavities.

Fig. 5 shows the swinging frame for the vent core plate.

Fig. 6 shows the core sections supporting rod.

Figs. 7 to 11 are views similar to Fig. 4 in different positions of the parts shown.

Fig. 12 shows the open frame for the cores.

Fig. 13 shows the oven for baking the cores.

Fig. 14 shows the core complete.

Fig. 15 shows means for applying the paste.

Fig. 16 shows enlarged the clutch device.

Fig. 17 shows the core boxes.

Fig. 18 shows inverted view of paste applying means.

Figs. 19 and 20 show the control device.

As set forth the machine comprises a frame having standards 2 and 3, in which is journaled a main shaft 4, which carries a support 5 for the mold box 6 fast thereto, whereby the shaft will swing the mold when turned. This shaft has loose thereon, a sleeve frame 7 which carries the mold box 8, similar to the mold box 6. These molds are mounted on their frames and are adjustable to varying heights of mold boxes by bolts 9, but the frames are made in two parts, the portion 10 in the form of an angle plate to which the molds are bolted being slideable on the outer parts 12, that are mounted on shaft 4, and sleeve 7 respectively, and are adjustable thereon by means of a lever 13 pivoted on the part 12, that carries a pin 14 working in a cam slot 15 on part 10, see Fig. 3. By these supporting means either of the molds can be shifted from horizontal position shown in Fig. 4 where they lie in the same horizontal plane, to that of Fig. 7 where the molds are engaged on the core face.

The shaft 4, and the sleeve frame 7, are actuated by any suitable controlling means, that will move them independently or together. By swinging the shaft and the sleeve, the molds can be brought from the position of Fig. 4 to that of Fig. 7, in which their core faces are brought together on a vertical plane, and the core sections will register. The two molds can now be swung from this position to that of Fig. 8, in which these faces are in a horizontal plane. They may then be returned to the horizontal position of Fig. 9 by swinging one mold back to normal position and then may be brought to the position of Fig. 10, and then to that of Fig. 11.

In Fig. 17 and in the other views, the molds 6 and 8 are shown provided with depressions 16, all of the same form, so that when the two mold faces are brought together as in Fig. 7, the depressions will register, each being a complementary half of the core. When in the open position, these depressions are filled with sand as usual, and generally a vent channel for air is provided in one of the meeting faces. Sometimes a wire frame 17 is inserted in one of the two sections of the cores, as indicated in Fig. 6. On one of the mold boxes as 8 a vent frame 18 is brought to bear, being hinged at 19 to swing down on the mold faces and cause grooves 20 therein, by ribs 21 on the plate 18, see Fig. 5. When the two molds have been thus prepared, they are treated with a coating of paste by a block 22. The supports are now swung to the position of Fig. 7, that will bring the mold faces together to engage the core sections, that will adhere because of the paste thereon. The two molds are then swung in this fixed relative position to the horizontal position of Fig. 8, and then the

mold 6, is moved upwardly by the lever 13, as indicated in broken lines in Fig. 8, since the two core sections will be now united by paste as indicated in Fig. 14. Then the mold 6 is swung back to the former horizontal position as shown in Fig. 4, but since it was shifted on the frame it will now take a lower position as indicated in Fig. 9. The next operation is to place the frame 63, see Fig. 12, on the mold 8, that will engage cores thereon, which frame may have suitable locking means on the corners. The mold 8 is now swung back on to the mold 6, as shown in Fig. 10, so that the carrier frame 63 will rest on the mold 6, and the cores 25 will rest on top of the carrier. The mold 8 is now swung over, as indicated in Fig. 11, and the cores 25 will remain on top of the frame 63. This frame is now simply lifted off of the mold 6, and the cores resting thereon are placed with this frame in the oven 27, as indicated in Fig. 13.

The shaft 4 and the sleeve frame 7, are provided with gear segments 28 and 29 respectively, that engage pinions 30 and 31 on shafts 32 and 33, as shown in Fig. 19. Each of these shafts is rotatable in bearings on frame 2 in a supporting block 34, and the pinions are always in mesh with their segments. On the shaft 32, see Fig. 16, are loosely mounted belt pulleys 35 and 36 driven in opposite directions from any suitable motor, and each pulley carries clutch levers 37, which engage a sleeve 38, slideable on shaft 33, but held from turning thereon by a key 39, between the shaft and sleeve. When this sleeve is moved toward one pulley, its tapered end will swing levers 37 against discs 40 and 41 on the pulley, that will now drive the shaft 32 in one direction; and one of said discs may be of friction material. The pulley 35 has similar levers 42 that will engage the opposite tapered end of sleeve 38, when shifted in the opposite direction. This pulley will now turn the shaft 32, but in the opposite direction, since the pulleys run reversely. A similar arrangement of two pulleys 43 and 44 with clutch members are controlled by sleeve 45 similar to sleeve 38. As shown in Fig. 19, these clutch sleeves are controlled by rocker arms, the sleeve 38 being engaged by arm 46 fast on shaft 47; while a shaft 48 has a rock arm 49 engaging sleeve 45. On one end of shaft 47, is an arm 50 with a pin 51, that is engaged by suitable cams on a cam wheel 52. Other cams on this wheel engage a pin 53 on an arm 54 fast on shaft 48. These cams are so arranged and located that the clutches are engaged to swing the shaft 4 and the sleeve frame 7, to cause swinging of the mold boxes 6 and 8 to the positions described with reference to Figs. 4-11 inclusive. The friction clutch will slip when the molds are brought together, and a stop 60 engages the

two mold frames when brought to the horizontal position of Fig. 4, or either one of them.

In Figs. 4 and 18 are shown the pasting block 22 having ribs 23 thereon of rubber or other material, which will have substantially outlined the core sections in the molds, and will serve for applying paste on the faces of the section beyond the vent groove, so 10 that the paste will not enter the groove that might interfere by stoppage. The plate 22 can have the ribs moved across a roller 61 in a paste box 62 to coat the face of the ribs.

In Fig. 12, is shown a transfer frame 64 comprising an outside frame 63 with cross plates 65 suitably shaped to receive the core 25. At the corners are projections 66 for attachment to the core box 6. Also retaining means in the form of spring clips 67 preferably located at two diagonally opposite corners to engage sockets 68 of the mold boxes, see Fig. 17.

To guard against separation of the two mold boxes as they travel together, from the 25 Fig. 7 position to that of Fig. 8 a lock member may be employed comprising a pin and hook as indicated at 69 in Fig. 1.

In the operation of the device the molds 6 and 8 are in the positions indicated in 30 Fig. 4, and sand is placed in the cavities as usual and the supporting rod may be also placed in one section. The plate 18 is then brought down and its ribs 21 will form the vent channel 30 in one section. The control wheel 52 is then turned whose cams will connect the clutches one on each shaft to turn the shafts in opposite directions and swing the molds up to position, Fig. 7. But previous to this operation the paste brush 40 22 is moved over the roller 61, and then applied to one section as indicated in Fig. 4 and removed. When the molds are thus swung up together the two sections will adhere and will form a complete core 25 as indicated in Fig. 14. Hand wheel is further advanced and suitable cams thereon will advance the molds to position of Fig. 8 which can be done by simply advancing frame 5 in the same direction that will swing 45 frame 7 with it. A stop member 60, will arrest the molds and their frames in this position, and will also serve to hold the molds, or either of them in the open position of Fig. 4, and in other positions. The

50 mold 6 must now be separated from the mold 8, which is done by swinging lever 13 for this mold that will move the mold upwardly on its frame 5 as indicated by broken lines in Fig. 8. The frame 6 is now 55 swung back to the former position to engage the stop 60, it will be seen that its face lies below the level of mold 8 on the opposite side because of the shifting by lever 13. The carrier frame 63 is now placed 60 on the mold 8 as indicated in Fig. 9, and will

be locked thereon, and engage each core. The next operation is to move the control whose cam will engage one clutch to swing the frame 7, back on top of the mold 6, as shown in Fig. 10. The frame 63 will be 70 carried with it and will now lie beneath the mold 8 and rest on the mold 6, the attachments of mold 6 reversing their supporting by the thickness of the carrier. This latter shift will reverse the carrier and bring the 75 cores to rest on top of the carrier as shown in Fig. 10. The last operation of the machine is to cause the mold 8 to be swung over to the opposite side as shown in Fig. 11, that will permit the removal of the carrier frame with the cores thereon, to be placed in the oven 27. It is only necessary to now return the mold 6 to its former position as shown in Fig. 4, in level with mold 8, which is done by lever 13.

A jarring device may be employed to insure proper separation of the mold boxes 80 6 and 8, and has one form as shown in these Figs. 1 and 8, comprising a hammer 70 having an arm 71, pressed by spring 72 against a notched disc 73. This disc is carried by pulley 74 on a swinging frame 75 with lever 76 that will bring this pulley against one of the belts 77 for the main pulleys.

What we claim is:—

1. In a core forming machine, a main frame, a pair of mold supports each movably mounted on the frame, whereby the molds can be swung independently to bring the faces together, and whereby the engaged molds can be swung together in fixed relative position, a driving member, and an automatic control member connecting the driving member with the mold supports and shiftable to a number of different positions, whereby control member will cause the molds to be first brought to opposite horizontal positions, then cause both molds to be swung to bring their faces together in a vertical plane, and then cause the engaged molds to be shifted to a position with said core faces horizontal and one mold inverted, and then cause the inverted mold to be shifted back to its normal horizontal position, said operations being effected in said sequence by successive advance movements of the control member.

2. In a core forming machine, a main frame, a pair of mold supports each movably mounted on the frame, whereby the molds can be swung independently to bring the faces together, and whereby the engaged molds can be swung together in fixed relative position, each mold being shiftable on its support in a direction perpendicular to its core face, a driving member and an automatic control member connecting the driving member with the mold supports and shiftable to a number of different positions, whereby the control member will cause the

4
molds to be first brought to opposite horizontal positions, then cause both the molds to be swung to bring their faces together in a vertical plane, and then cause the engaged 5 molds to be shifted to a position with said core faces horizontal and one mold inverted, and then cause the inverted mold shifted back to its normal horizontal position, said operations being effected in said sequence 10 by successive advance movements of the control member.

3. In a core forming machine, a main frame having a supporting shaft journaled therein, a mold support mounted on said 15 shaft, a second shaft in the form of a sleeve surrounding said shaft, a mold support on the second shaft, whereby the supports can be swung independently in opposite directions to bring the molds together with their 20 faces engaged, and whereby the engaged molds can be swung together in fixed relative position, a driving member, and an automatic control member for the supports shiftable to a number of different relative 25 positions whereby the control member will cause the molds to be first brought to opposite horizontal positions, then cause both molds to be swung to bring their faces together in a vertical plane, and then cause the engaged 30 molds to be shifted to a position with said core faces horizontal and one mold inverted, and then cause the inverted mold shifted back to its normal horizontal position, said operations being effected in 35 said sequence by successive movements of a control member arranged to connect the mold supports with said power device.

4. In a core forming machine, a main 40 frame having a supporting shaft journaled therein, a mold support on said shaft, a second shaft in the form of a sleeve surrounding said shaft, a mold support on the second shaft, whereby the supports can be swung independently in opposite directions to bring 45 the molds together with their faces engaged and whereby the engaged molds can be swung together in fixed relative position, each mold being shiftable on its support in a direction perpendicular to its core face, a 50 driving member, and an automatic control member for the supports shiftable to a number of different relative positions, whereby the control member will cause molds to be first brought to opposite horizontal 55 positions, then cause both molds to be swung to bring their faces together in a vertical plane, and then cause the engaged molds to be shifted to a position with said core faces horizontal and one mold inverted, and then cause the inverted mold to be shifted 60 back to its normal horizontal position, said operations being effected in said sequence by successive movements of the control member arranged to connect the mold 65 supports with said power device.

5. In a core forming machine, a main frame having a supporting shaft journaled therein, a mold support mounted on said shaft, a second shaft in the form of a sleeve surrounding said shaft, a mold support on the second shaft, each mold being slidably mounted on its support, in opposite directions to bring the molds together with their faces engaged, and whereby the engaged molds can be swung together in fixed relative position, a control device comprising a pair of shafts driven in opposite directions and each carrying a clutch member, a clutch element shiftable to engage either of said clutch members to be thereby turned in opposite directions, said clutch element being connected with said mold support shaft, a second driving member comprising a clutch element connected with said sleeve, and a pair of clutch members driven in opposite directions arranged to be engaged alternately by said latter clutch element, a control member, and means connected the control member with said two shiftable clutch elements whereby advance of the member will cause the molds to be first brought to opposite horizontal positions, then both molds swung to bring their faces together in a vertical plane, and then shift the engaged molds to a position with said core faces horizontal and one mold inverted, and then to shift the mold that was inverted back to its upright position.

6. In a core forming machine, a main frame, a pair of mold supports each movably mounted on the frame, whereby the molds can be swung independently to bring the faces together, and whereby the engaged molds can be swung together in fixed relative position, one of said molds being shiftable on its support in a direction perpendicular to its face, and a cam lever on the support to so shift the mold.

7. In a core forming machine, a main frame having a shaft journaled therein, a mold support mounted on said shaft, a second shaft in the form of a sleeve surrounding said shaft, a mold support on the second shaft, whereby the supports can be swung independently in opposite directions to bring the molds together with their faces engaged, and whereby the engaged molds can be swung together in fixed relative position, each mold being independently shiftable on its support in a direction perpendicular to its core face.

8. In a core forming machine, a main frame having a supporting shaft journaled therein, a mold support mounted on said shaft, a second shaft in the form of a sleeve surrounding said shaft, a mold support on the second shaft, whereby the supports can be swung independently in opposite directions to bring the molds together with their faces engaged, and whereby the engaged

molds can be swung together in fixed relative position, each mold being independently shiftable on its support in a direction perpendicular to its core face, and means for shifting the mold supports.

9. In a core forming machine, a main frame having a supporting shaft journaled therein, a mold support mounted on said shaft, a second shaft in the form of a sleeve surrounding said shaft, a mold support on the second shaft, whereby the supports can be swung independently in opposite directions to bring the molds together with their faces engaged, and whereby the engaged molds can be swung together in fixed relative position, each mold being independently shiftable on its support in a direction perpendicular to its core face, and means for

shifting the mold supports independently and also shifting the mold supports in fixed relative position. 20

10. In a core forming machine, a main frame, a mold support movably mounted on said frame, a second mold support movably mounted on the frame, whereby the molds supports can be swung to bring the mold faces together, and whereby the engaged molds can be swung together in fixed relative position, each mold being independently shiftable on its support in a direction perpendicular to its core face. 25 30

Signed at New York city, N. Y., on July 17th, 1924.
